TO WESTERN CARTRIDGE COMPANY, OF EAST ALTON, ILLINOIS, A CORPORATION
OF DELAWARE.

METHOD AND MACHINE FOR MAKING DETONATOR CONNECTIONS.

Original application filed December 30, 1922, Serial No. 609,954. Patent No. 1,626,118, dated April 26, 1927. Divided and this application filed January 28, 1925. Serial No. 5,395.

This invention relates to detonators and more particularly to those of the electrical-
ly ignited type. This application is a division
5 of application Serial Number 609,954,
filed December 30, 1922, now Patent No.
1,626,118, granted April 26, 1927.

One of the objects of this invention is to provide improved processes and mechanisms, whereby the detonators, and more particularly
10 10 the igniter connections, may be made economically, with accuracy and in order to produce an article which will be reliable and simple.

Another object of this invention is to provide an improved detonator and more particularly improved igniter connections therefor.

Further objects will appear from the detail description taken in connection with the
20 accompanying drawings, in which:

Figure 1 is a sectional view of a detonator embodying this invention;

Figure 2 is a detail perspective view illustrating the attaching of the filament to the
25 terminals and the plating of this filament and terminals;

Figure 3 is a perspective view of the igniter plug before assembling the filament;

Figure 4 is a plan showing the apparatus
30 for attaching the filament to the terminals and plating the same;

Figure 5 is a section on line 5—5, Figure 4;

Figure 6 is a section on line 6—6, Figure 4; and

Figure 7 is a perspective view showing the completed igniter.

Referring to the accompanying drawing, and more particularly to Figure 1, the detonator, as shown, comprises a shell 1 which may be of drawn metal and has charge components 2 and 3 of any improved composition and arrangement, and the upper end of this shell is beaded as shown at 4. In this
45 shell are arranged the terminals 5 of the connections 6 which pass through a plug 7 formed on the connections and of a suitable composition, a satisfactory one being a mixture of sulphur and graphite. The connec-
50 tions are insulated wires which are stripped from where they project through the plug

and these connections are formed, as hereinafter described, to receive the filament 8. This filament may be of any suitable resistance wire, a satisfactory one being of a composition of nickel, iron and copper. In order, however, to secure this filament to the terminals they are dipped in solder which also serves to coat or plate the filament as well as the connections, in order to protect them against deterioration when in the shell. The plug and its terminals are secured within the shell by additional plugs 9 and 10 of sulphur and pitch, which serve to seal and cap the shell and the terminals therein. These plug components are poured into the shell so as to flow around the connections, and it will be noted that the composition flows into the bead 4 so as to firmly secure and lock the parts together.

The plug 7 may be formed on the connections 6 by casting the same in place on the connections. The protruding ends of the connections may then be stripped of their insulation to form the terminals which are then notched at their ends as shown in Figure 3. A method and apparatus for notching the terminals are fully described in the above-named application.

Referring to Figures 2 and 4 to 7 inclusive, 80 73 designates a solder pot, which is provided with molten solder, and on one side of this pot is supported a reel 74 while on the other side are the stationary and movable parts 75 and 76, respectively, of a combined cutter and clamp, whereby a strand of the filament wire 77 may be stretched across the pot and clamped on one side thereof.

Assuming the filament wire to be stretched over the solder and clamped as shown in Figure 2, the terminals 5 projecting from the plug 7 are placed in aligned relation, with the notches in the terminals taking over the wire. The plug and terminals are now moved down, carrying the wire with them 95 into the solder and thereby not only causing the wire to be soldered to the terminals, but also coating the wire as well as the terminals with a plating of the solder. It will be understood, of course, that the terminals are 100 first dipped in a suitable flux before immersion into the solder; the solder can be of any

suitable composition, such as a lead tin alloy. After the wire has been soldered to the terminals, the plug and terminals are moved to the right, as the combined cutter 5 and clamp 75-76 is opened, until the wire to the left of the terminals is in cooperation with the cutter and clamp. The latter is then closed, thereby cutting off the wire connected to the terminals and also clamping 10 the wire in stretched condition across the solder pot. If for any reason it is desirable to retain a plurality of terminals connected together on the single filament wire it will be obvious that the cutting off of the 15 wire connected to the terminals as just described, can be postponed. In other words, the cutting or severing of the wire between completed detonators may be accomplished at any desirable time.

Referring now to Figures 4 to 6 inclusive, the solder pot 73 is shown as provided with an electrical heating element 78, and mounted on a suitable base 79 on which the reel 74 may also be mounted. The wire 77 passes 25 through a groove 80 formed between two plates 81 on the base, and after passing over the solder pot passes through a groove 82 between two plates 83 and 84 on the base. The plate 84 has mounted thereon a cutter blade 85, which cooperates with the cutting face 86 on the plate 83, and this cutter is normally held on the face 86 by a spring 87, while it is moved against the tension of the spring by a knob 88. It will be understood that the filament wire is thin and 30 very flexible, so that the end of this wire becomes wedged between the cutting faces in order to provide a clamp.

Pivoted on the base are a pair of counter-weighted arms 89 and 90 which are held in proper position against stops 91 on the base. These arms are provided with tips 92, which are preferably of glass in order to be transparent, and which are spaced to provide a 45 groove or passage 93 therebetween, which is of sufficient width to receive the terminals 5.

In operation the terminals are placed in the groove 93 between the tips 92 and downward pressure is applied to the plug, thereby causing the tips which are engaged by the 50 plug to move downwardly with the terminals and wire into the solder. In order to solder the wire to the terminals and plate this wire as well as the terminals, these tips, however, not only provide a guide securing the proper engagement of the terminals with the wire, but they also provide stops for limiting the dipping movement, as this 55 downward movement is arrested by engagement of the arms 89 and 90 with the top of the pot. Moreover since the tips are of an insulating material, they will protect the sulphur composition plug against heat and prevent it from burning, charring or melting. 60 The grooves 80, 82 and 93 provide guides

whereby the wire may be readily restrung over the solder after a filament has been attached to the terminals. It will be understood, of course, that the ends of the wire are suitably trimmed off as shown in Figure 7. This trimming may be accomplished 70 at any suitable time and does not necessarily have to be done the instant the terminals to which the filament has been attached are removed from the soldering mechanism. 75

It will, therefore, be seen that this invention accomplishes its objects. By the process and mechanism described the detonator can be made with a minimum of expense; however, the operations are so performed that each operation will effectively secure its objects and accurately prepare the subject matter for the succeeding operation. A detonator is provided which is of improved construction and which is not subject to deteriorating while it is convenient for use as well as shipment.

It is obvious that various changes may be made in details without departing from the spirit of this invention; it is, therefore, to be understood that this invention is not to be limited to the specific details shown and described.

Having thus described the invention, what is claimed is:

1. In the art of making detonators, the process comprising, placing the terminals of the igniter connections on the filament, and immersing the assemblage in solder.
2. In the art of making detonators, the process comprising, placing the formed terminals of the igniter connections over the filament, and immersing the assemblage in solder.
3. In the art of making detonators, the process comprising, placing the terminals of the igniter connections on a filament wire, immersing the terminals and wire in solder, and severing the filament forming portion from the wire.
4. In the art of making detonators, the process comprising, placing the terminals of the igniter connections on a stretched filament wire, and immersing the terminals and wire in solder.
5. In the art of making detonators, the process comprising, placing the terminals of the igniter connections on a wire stretched above the solder, and dipping the terminals and the wire into the solder.
6. In the art of making detonators, the process comprising, placing the terminals of the igniter connections, projecting through a plug thereon, on a filament wire, and immersing the terminals and wire in solder.
7. In the art of making detonators, the process comprising, placing the terminals of the igniter connections, projecting through a plug thereon, in alined relation on a fila- 130

ment wire, and immersing the terminals and wire in solder.

8. In the art of making detonators, the process comprising, fastening a stretched wire at one end, securing the igniter connection terminals to the wire, and shifting the connected terminals and wire in order to refasten the wire.

9. In the art of making detonators, the process comprising, fastening a stretched wire at one end, securing the igniter connection terminals to the wire, and shifting the connected terminals and wire in order to refasten and stretch another length of the wire.

10. In the art of making detonators, the process comprising, fastening a stretched wire at one end, securing the igniter connection terminals to the wire, and shifting the connected terminals and wire in order to refasten and stretch another length of the wire while the length secured to the terminals is cut.

11. In the art of making detonators, the process comprising, fastening a stretched wire at one end, placing the igniter connection terminals on the wire, dipping the terminals and wire in solder, and shifting the connected terminals and wire in order to refasten the wire and stretch another length of the wire.

12. In a machine for making igniter connections, the combination with a solder pot, of means adapted to stretch a filament wire over said pot, whereby the filament-receiving terminals may be placed on the wire and immersed with the terminals into the solder.

13. In a machine for making igniter connections, the combination with a solder pot, of a holder adapted to secure one end of a filament wire in order to stretch the same over said pot, whereby the filament-receiving terminals may be placed on the wire and immersed with the terminals into the solder.

14. In a machine for making igniter connections, the combination with a solder pot, of means for guiding a filament wire over said pot, whereby the filament-receiving terminals are adapted to be placed on the wire and immersed with the terminals into the solder.

15. In a machine for making igniter connections, the combination with a solder pot, of means for guiding a filament wire over said pot, and means adapted to secure one end of said wire, whereby the filament-receiving terminals are adapted to be placed on the wire and immersed with the terminals into the solder.

16. In a machine for making igniter connections, the combination with a solder pot, of a filament wire reel on one side of said pot, and a holder adapted to secure the wire on the other side of said pot.

17. In a machine for making igniter con-

nections, the combination with a solder pot, of a holder adapted to releasably secure one end of a filament wire in order to stretch the same over said pot.

18. In a machine for making igniter connections, the combination with a solder pot, of a holder adapted to releasably secure one end of a filament wire in order to stretch the same over said pot, and a cutter associated with said holder.

19. In a machine for making igniter connections, the combination with a solder pot, of a cutter adapted to sever a filament wire and hold the end thereof in order to stretch the wire over said pot.

20. In a machine for making igniter connections, the combination with a solder pot, of a cutter adapted to sever a filament wire and releasably hold the end in order to stretch the wire over said pot.

21. In a machine for making igniter connections, the combination with a solder pot, of means adapted to stretch a filament wire over said pot, and means for guiding the filament-receiving terminals on the wire.

22. In a machine for making igniter connections, the combination with a solder pot, of means adapted to stretch a filament wire over said pot, and means for alining the filament-receiving terminals with the wire.

23. In a machine for making igniter connections, the combination with a solder pot, of means adapted to stretch a filament wire over said pot, and means for guiding the filament-receiving terminals in alined relation on the wire.

24. In a machine for making igniter connections, the combination with a solder pot, of means adapted to stretch a filament wire over said pot, and means adapted for movement towards said pot, for guiding the filament-receiving terminals on the wire.

25. In a machine for making igniter connections, the combination with a solder pot, of means adapted to stretch a filament wire over said pot, and means engageable by a plug on the connections adapted to guide the terminals projecting beyond the plug on the wire.

26. In a machine for making igniter connections, the combination with a solder pot, of means adapted to stretch a filament wire over said pot, and means arranged for movement towards said pot, and engageable by a plug on the connections, adapted to guide the terminals projecting beyond the plug on the wire.

27. In a machine for making igniter connections, the combination with a solder pot, of a holder adapted to secure one end of a filament wire in order to stretch the same over said pot, and means for guiding the filament-receiving terminals on the wire.

28. In a machine for making igniter connections, the combination with a solder pot,

of means for guiding a filament wire over said pot, and means for guiding the filament-receiving terminals on the wire.

29. In a machine for making igniter connections, the combination with a solder pot, of means for guiding a filament wire over said pot, means adapted to secure one end of said wire, and means for guiding

the filament-receiving terminals on the wire.

In testimony whereof we affix our signatures this 6th day of June, 1924.

JOHN M. OLIN.

JOHN B. SMITH.

In testimony whereof I affix my signature this 11th day of August, 1924.

VICTOR L. DAVIS.
